His Attorney.

UNITED STATES PATENT OFFICE

JAMES L. McFARLAND, OF SCHENECTADY, NEW YORK, ASSIGNOR TO GENERAL ELECTRIC COMPANY, A CORPORATION OF NEW YORK

FURNACE

Application filed April 19, 1929. Serial No. 356,534.

My invention relates to furnaces, more particularly to furnaces for brazing and annealing and the like, and has for its object the provision of a simple, reliable and efficient 5 method and means for operating a furnace of this character.

Although my invention is not limited thereto, it has particular application in the 10 operation of furnaces for carrying out certain heating operations for metals, such as brazing and annealing, in an atmosphere of a selected gas, such as hydrogen, which prevents oxidation of the metal during the heating 15 operation. One form of such a furnace is disclosed and claimed in the copending United States application of Carl L. Ipsen and James L. McFarland, Serial No. 236,530, filed November 29, 1927, and assigned to the same assignee as this invention.

20 In the arrangement there described, the furnace chamber is filled with a selected gas, preferably of hydrogen content, through which the articles to be treated are passed. A portion of this chamber at the inlet end is 25 heated to a suitable high temperature to melt the brazing metal and form a brazed joint while the remaining portion of the furnace constitutes a cooling chamber.

In order to produce uniform work and a 30 maximum output commensurate with the operating cost, it is desirable to use either pure hydrogen as the working medium or a gas mixture comprising hydrogen in fairly large proportions such as 20-80% by volume.

35 In either case the gas medium will be explosive in character. By this it will be understood that if the gas medium is mixed with air and if this resultant gas mixture is heated or ignited a violent chemical action will take 40 place accompanied by a flame and explosion. This action consists in the sudden combination of the hydrogen and oxygen constituents of the mixture to form water. The temperature to which the gas mixture must be heated 45 to cause this chemical action is well within the furnace operating temperature.

It will be appreciated, therefore, that it is 50 very important to prevent air from mixing with the furnace working gas medium, particularly when this gas is heated to the fur-

nace working temperature. I have found, however, that in starting a furnace of this character it is desirable, from the standpoint of economy both with respect to the gas used and to the time required, to first heat the 55 furnace, which is filled with air, substantially to its working temperature and then fill the furnace with the working gas. Moreover, it is desirable at times to cool the furnace quickly so that it may be opened to the outside air as for example in case the operation of the furnace must be interrupted 60 temporarily for internal repairs. To allow such a furnace to cool to a safe temperature at its natural rate requires from several days to a week's time, the time required depending upon the size of the furnace being cooled. Obviously this is an undesirable condition. In one of its aspects, my invention contemplates the provision of a simple, efficient and 65 safe method of filling the furnace with the working gas, irrespective of the furnace temperature, and moreover, for quickly cooling the highly heated furnace to a safe temperature at which it may be opened to the outside air.

In carrying my invention into effect in one form thereof, I start up the furnace first by heating it substantially to its working temperature. In order to render the furnace safe for the reception of either pure hydrogen or of a gas of hydrogen content, which is explosive in character, I introduce a gas which is non-explosive in character, to expel the air from the furnace. This gas may be and preferably is a non-explosive mixture of hydrogen and nitrogen. However, nitrogen alone may be used. After the furnace has been purged of the air I supply the furnace with the working gas. In the event it becomes necessary to cool the furnace rapidly so that it may be opened to the outside air, I introduce a non-explosive gas as for example nitrogen, in sufficient quantities either to render the working gas non-explosive in character or to 85 purge the furnace of the working gas. The furnace may then be opened. To enhance the cooling operation, air may be forced through the furnace. Of course the air will be forced through only after the working gas has 90 95 100

been rendered non-explosive in character or the furnace has been purged of the working gas.

For a more complete understanding of my invention, reference should be had to the accompanying drawing in which Fig. 1 is a side elevation of an electric brazing furnace embodying my invention; Fig. 2 is an end elevation partly in section of a portion of the furnace, the elevation being to a larger scale than Fig. 1; and Fig. 3 is a section along the line 3—3 of Fig. 1 looking in the direction of the arrows.

Referring to the drawing, I have shown my invention in one form in connection with an electric brazing furnace in which a hydrogen gas is selected for the working medium. Preferably, the furnace will be of the form described in the aforementioned copending application of Carl L. Ipsen and James L. McFarland. Briefly, the construction and operation of this furnace is as follows: As shown, the furnace comprises a cylindrical gas-tight steel shell or casing 10 defining an elongated furnace chamber, this shell being supported in a horizontal and elevated position by means of a plurality of steel columns 11. Inside the shell at the inlet end are top, bottom and side walls 12 made of heat refractory bricks and defining a horizontal heating chamber 13 provided with relatively small inlet and outlet passages 13a and 13b. Suitable heating means, such as electrical heating resistors 15 (Fig. 2), is provided in the heating chamber 13, these resistors being hung on suitable heat refractory electrically insulating projections or supports 16 built in the furnace wall. It will be understood that suitable terminals for the heating units are brought out for connection to a suitable electrical supply source through openings 17. Inlet and outlet openings 18 and 19 respectively for the charge are provided in the bottom of the shell in opposite ends thereof. Access may be had to the interior of the shell for repairs, if necessary, through bulk heads 20 provided with removable covers.

The heating portion or chamber 13 and the connecting passages 13a and 13b occupy but a small portion of the total length of the furnace. The remaining portion of the furnace constitutes a cooling chamber, a substantial portion of which is provided with a water jacket (Fig. 3) through which cooling water 22 is circulated. Suitable inlet and outlet openings 23 and 24 respectively for the water are provided in the bottom and top portions of the furnace.

It will be understood that the articles to be heated are inserted into the heating chamber through the inlet opening 18 and move at a substantially uniform rate through the heating and cooling chambers to the opposite end where they are removed through the outlet opening 19.

Two series 25 and 26 (Figs. 2 and 3) of tracks extending through the chamber are provided for the articles. The metal articles 27 to be brazed, shown as an assembly of parts with brazed material at the joints constituting a portion of an electric refrigerator, are provided with suitable supporting trays or supports 28 (Fig. 3) upon which they are supported in spaced relation. It will be understood that these trays 28 are moved through the heating chamber on the rollers 25 and 26.

Suitable elevating means is provided just below each opening 18 and 19, comprising suitable counter-weighted platforms or elevators 35 and 36. Each elevator is operably connected with a suitable operating motor 37 which preferably will be of the fluid type. It will be understood that when the elevators are raised, a tray may be pushed from the elevator 35 into the heating chamber and at the same time a tray received from the cooling chamber onto the elevator 36. The trays are pushed through the furnace by means of a hydraulic motor 40 having a pusher piston 41 which extends through an opening in the inlet end of the furnace in position to engage the trays.

The openings 18 and 19 will be suitably sealed during the operation of the furnace so as to conserve the selected gas and thus the heat. Thus these openings will be only slightly larger than the trays and moreover will be normally closed by the elevators which ordinarily remain in their raised positions. Preferably, also, the openings 18 and 19 are each provided with a pair of doors 43 which will be opened by the upward movement of the elevators and will be closed as the elevators are lowered. The heat will also be preserved to a great extent by means of the articles 27 and their support (Fig. 2) which practically close the passages 13a and 13b leading to and from the heating chamber.

It will be understood that in the operation of the furnace, the heating and cooling chambers will be maintained filled with the selected working gas medium which preferably will be admitted through a pipe 44 communicating with the top of the cooling chamber. It will be understood that the working gas will be supplied continuously to the furnace chamber. In order to insure that the furnace chamber pressure is at all times above atmospheric pressure and thus in order to insure that the working gas medium is being supplied continuously to the furnace in a quantity and at a pressure sufficient to prevent the leakage of air into the furnace, the furnace will be provided with a small duct or tube 44a communicating with the furnace chamber through which the working gas may escape. The gas escaping from this duct is ignited, combustion taking place at the outlet end of the tube. In the event the flame disap-

pears, the attendant will be warned that the furnace pressure is below the desired value. The working gas supply will then be increased so as to bring the furnace pressure to the full working value.

As has been pointed out in starting up the furnace, it is desirable to fill the furnace with the working medium after the furnace has been heated substantially to its full operating 10 temperature which is about 1100° C. In order to render the furnace safe for the reception of the working medium, I first purge the furnace of the air, which normally will be present by introducing a non-explosive gas 15 into the furnace. Preferably this gas will be a non-explosive mixture of hydrogen and nitrogen.

The purging mixture preferably will be admitted through a pipe 45 communicating 20 with the furnace chamber at the bottom thereof while the air diluted with the purging gas will be allowed to escape through the pipe 44. It will be understood, of course, that during this operation the pipe 44 will 25 be disconnected from the source of working gas supply by suitable valve means (not shown) and open to the outside air to allow the escape of the air. Moreover, it will be understood, of course, that these pipe 30 connections may be reversed. Thus the non-explosive purging mixture may be admitted by means of the pipe 44 while the air mixture will be allowed to escape through the pipe 45. It may be desirable not to use a 35 mixture of nitrogen and hydrogen but to use pure nitrogen in the purging operation. The method of introducing the purging gas in either case will be the same.

When it is found that the gas escaping 40 from the furnace is non-explosive in character, the furnace is safe for the reception of the working medium. It will be understood that suitable gas tests will be made to determine the air content before the furnace will 45 be supplied with the working medium. The gas may be tested conveniently by the ordinary test tube method. Thus the gas may be collected in a test tube and a flame be applied to the open end of the tube to determine 50 whether or not the gas is inflammatory. If pure hydrogen be selected as the working gas medium the pure hydrogen will be admitted to the furnace in sufficient quantity to purge the furnace of the air purging gas. 55 If a mixture of hydrogen and nitrogen be selected, the working gas may be supplied by either of two methods. Thus after the air purging operation, pure hydrogen may be admitted to bring the purging gas up to the 60 full required hydrogen content. On the other hand, it may be more convenient to introduce a previously prepared working mixture of the hydrogen and nitrogen. Thus the working mixture itself may be admitted 65 in quantity sufficient to purge the furnace

of the air purging gas. If pure nitrogen had been used to purge the furnace of the air, preferably pure hydrogen will be admitted in proper proportions to form the working mixture. Regardless of which of 70 these methods of supplying the furnace with the working gas is used, either the pure hydrogen or the previously prepared working mixture of hydrogen and nitrogen may be admitted either by the pipe 44 or by the 75 pipe 45 it being understood that suitable valve means (not shown) will be provided to control the sources of gas supply.

After the furnace has been supplied with the working gas, the trays carrying the articles to be heated will be pushed through the furnace in end-to-end relation by means of the piston 41. It will be understood that the articles will be suitably inserted and removed 80 from the furnace chamber by means of elevators 35 and 36. Preferably the motors provided to operate the elevators 35 and 36 and the pusher motor 40 will be suitably interlocked by means (not shown) to establish a 85 predetermined sequence of operation of the elevators and pusher mechanism.

In the event that it is necessary to cool the furnace quickly as for example in case the operation of the furnace must be temporarily interrupted for interior repairs, the 90 working medium will be first driven out or rendered non-explosive in character. Thus the working medium may be driven out by a non-explosive gas in a manner similar to the air purging process previously described, 95 after which the furnace may be opened to the outside air and thus cooled rapidly, or the working medium may be rendered non-explosive by the introduction and mixture therewith with the furnace closed of a sufficient quantity of the non-explosive gas after 100 which the furnace may be opened. The non-explosive gas may be a non-explosive mixture of hydrogen and nitrogen or pure nitrogen alone may be used for either of these operations. 105 If the purging method is selected, the purging gas may be admitted through the pipe 45, while the working gas diluted with the purging gas will be allowed to escape through the top of the furnace by means of 110 the pipe 44. When it is found that the gas escaping through the pipe 44 is non-explosive in character, as determined by a suitable test, the furnace can be opened and air admitted for rapid cooling. If desired, the 115 purging gas may be admitted through the pipe 44 so as to force the working medium through the bottom opening 45. If it be desired to use the second method, i. e., if it be desired to render the working gas 120 non-explosive in character before opening the furnace, the nitrogen gas or the non-explosive mixture of hydrogen and nitrogen may be admitted through either the 125 pipe 44 or the pipe 45 with the furnace 130

chamber otherwise closed. Under these conditions it will be understood that a sufficient quantity of the non-explosive gas will be admitted to bring the furnace chamber 5 gas within the non-explosive range, as determined by a suitable test, after which the furnace may be opened to the outside air.

To enhance the cooling operation, cooling air may be forced through the furnace chamber after it has been purged of the working gas or this gas has been rendered non-explosive in character. Thus the bulkheads 20 may be removed and the inlet and outlet openings 18 and 19 be opened so that air 15 will be circulated through the furnace chamber by natural draft action. Or air may be forced through the furnace from one of its ends while the opening 18 or 19 at the opposite end will be opened to permit a free 20 circulation of the air.

While I have in accordance with the provisions of the patent statutes described my invention as embodied in concrete form and operating in a specific manner, it should be 25 understood that I do not limit my invention thereto, since various modifications thereof will suggest themselves to those skilled in the art without departing from the spirit of my invention, the scope of which is set 30 forth in the annexed claims.

What I claim as new and desire to secure by Letters Patent of the United States, is:

1. The method of operating a furnace wherein a working medium explosive in 35 character is used in the furnace chamber which comprises heating said furnace chamber substantially to its operating temperature while filled with air, then admitting a non-explosive medium to purge the heated 40 furnace chamber of air and thereafter supplying the furnace chamber with said working medium.

2. The method of operating a brazing furnace wherein a working gas of hydrogen 45 content is used which comprises heating said furnace substantially to its working temperature while filled with air, then admitting a non-explosive gas to purge the heated furnace of air and thereafter admitting hydrogen to form the working medium.

3. The method of operating a brazing furnace which comprises heating said furnace to its working temperature while filled with air, then admitting a non-explosive 55 mixture of hydrogen and nitrogen to purge the heated furnace of air and thereafter admitting hydrogen in sufficient quantity to form a working medium.

4. The method of cooling a furnace where- 60 in a working medium explosive in character is used which comprises admitting a non-explosive medium to the furnace in sufficient quantity to render the furnace gas non-explosive in character and thereafter opening 65 said furnace to the outside air.

5. The method of quickly cooling a furnace wherein a working medium explosive in character comprising a hydrogen gas is used which comprises forcing nitrogen into said furnace in sufficient quantity to obtain a furnace gas non-explosive in character and thereafter forcing cooling air through said furnace.

6. The method of quickly cooling a furnace chamber wherein a working medium explosive in character comprising a hydrogen gas is used which comprises forcing nitrogen into the furnace chamber so as to purge the chamber of the explosive working medium and thereafter admitting cooling air to the chamber.

In witness whereof, I have hereunto set my hand this 18th day of April, 1929.

JAMES L. McFARLAND.
